UNITED STATES PATENT OFFICE.

LEVI R. ROCKWOOD, OF WORCESTER, MASSACHUSETTS, ASSIGNOR OF ONE-HALF TO F. LINUS CHILD, OF SAME PLACE.

PALETTE AND RESERVOIR FOR STENCILING-INK.

SPECIFICATION forming part of Letters Patent No. 257,386, dated May 2, 1882.

Application filed December 19, 1881. (No model.)

To all whom it may concern:

Be it known that I, LEVI R. ROCKWOOD, of Worcester, in the county of Worcester and State of Massachusetts, have invented certain new and useful Improvements in Combined Palette and Stand for Stenciling Inks or Colors; and I declare the following to be a description of my said invention sufficiently full, clear, and exact to enable others skilled in the art to which it appertains to make and use the same, reference being had to the accompanying drawings, which form a part of this specification.

The object of my present invention is to provide a practical and convenient apparatus for containing and delivering inks or colors as employed for stenciling or marking packing-cases and for similar purposes, said apparatus being adapted to preserve the ink in a proper condition, and to deliver to the brush only so much as is required at the time of use; also, to prevent waste by excessive delivery or accidental upsetting of the receptacle, and to give a conveniently portable form for carrying from place to place without liability of spilling the ink or color. I attain these objects by an apparatus constructed as shown in the accompanying drawings and hereinafter described.

Figure 1 is a perspective view of my improved stenciling-palette and color-stand. Fig. 2 is a plan view of the same, a portion of the top being shown broken away to reveal parts beneath. Fig. 3 is a central vertical section at line *x x*, Fig. 2.

The part marked A is a flat disk or plate, preferably of brass or other suitable metal, which serves as a palette for distributing the ink or color upon the brush.

B indicates a reservoir or cylinder for containing the ink, which is used in a liquid or semi-liquid form. Said cylinder B is mounted upon the plate A near one side, and its interior chamber, B', communicates by a suitable passage or chamber, *b*, with a small orifice, *a*, formed through the plate A near its center. The surface of the plate A is slightly depressed around the opening *a*, as indicated.

The piston C is arranged within the cylinder

chamber B', and a screw, D, is connected therewith, by means of which said piston can be adjusted up or down within the cylinder, the end of the screw D being swiveled to the piston at *d*, and its thread fitted to the nut or cap E on the top of the cylinder. If desired, the cap E can be fitted to tightly close the top of the cylinder, and a stuffing-box may be arranged about the screw, as shown, although I do not in all cases desire to use the stuffing-box.

A suitable handle is fixed on the top end of the screw D, by which the screw can be turned, and which also serves as a convenient means for lifting and carrying the apparatus.

A ring or other device, F, is fixed to the side of the cylinder B for holding the stencil-brush G when it is not in use, as shown in Figs. 1 and 2.

A screw-stopper, H, is arranged in the top of the reservoir for convenience of filling it with ink or coloring material, the stand being inverted for the purpose; or, if preferred, the top cap, E, and piston C can be removed for filling the reservoir from the top.

A small screw or plug, I, is provided for stopping the orifice *a*, as illustrated, which plug can be attached by a cord or chain, *i*, to a convenient part of the apparatus.

When it is desired to use the apparatus the stopper I is removed and the screw D turned, so as to slightly depress the piston C, thus causing a sufficient quantity of the ink to be delivered through the opening *a* upon the palette A, where it can be taken upon the brush as required by passing the brush back and forth on the surface of the palette.

Surplus ink can be drawn back into the cylinder by raising the piston.

Ink or color in a viscid or semi-liquid condition can be employed with this apparatus, as the ink is so confined as to preserve it from the atmosphere, except such portion as is for immediate use, and being so confined the apparatus is rendered cleanly for use and not liable to have its contents accidentally distributed by the overturning of the apparatus.

If desired, the plate A may be mounted upon a wood block, and the back of the cylinder may be provided with a hook, so that it can

be hung upon the edge of a box or other convenient support when required.

I am aware that inkstands have been made wherein the ink is forced upward in a tube by pressure of air within an inclosed chamber regulated by a screw, and I do not therefore herein claim such feature, broadly.

What I claim as of my invention, and desire to secure by Letters Patent, is—

19. 1. The within-described portable apparatus for containing and delivering stenciling ink or color of a viscid or semi-liquid nature, consisting of the flat disk or palette-plate having a small orifice in its surface and a reservoir connected therewith, from which the color or ink is mechanically forced upon said palette through said orifice, said apparatus being adapted for use in the stenciling or marking of packing-eases, substantially as herein set forth.
20. 2. The combination of the flat circular pal-

ette A, having the central orifice, a, the reservoir-cylinder B, mounted upon the side of said palette, with passage b communicating therewith, the piston C, fitted within said cylinder, 25 and the long screw D, arranged for moving said piston, all constructed and operating substantially as and for the purpose hereinbefore described.

3. The combination of the palette-plate A, 30 having orifice a, the cylinder B, communicating therewith, the piston C, the screw D, the cap E, the brush-holder F, and the stopper I, substantially as shown, and for the purpose set forth.

Witness my hand this 13th day of December, A. D. 1881.

LEVI R. ROCKWOOD.
